UNITED STATES PATENT OFFICE

120,687

DESIGN FOR A PNEUMATIC TIRE

Lawrence G. Moonan, Detroit, Mich., assignor to
United States Rubber Company, New York,
N. Y., a corporation of New Jersey

Application February 14, 1939, Serial No. 82,977

Term of patent 14 years

To all whom it may concern:

Be it known that I, Lawrence G. Moonan, a citizen of the United States of America, residing in Detroit, county of Wayne, State of Michigan, have invented a new, original, and ornamental Design for a Pneumatic Tire, of which the following is a specification, reference being had to the accompanying drawing, forming part thereof, wherein:

Figure 1 is a perspective view of a portion of a

tire, partly in dotted lines, showing my new design;

Figure 2 is a plan view of a section of the tire; and,

Figure 3 is a transverse sectional view, taken along line III—III of Figure 2.

I claim:

The ornamental design for a pneumatic tire, as shown.

LAWRENCE G. MOONAN.
